E. S. STAUFFER

Des. 160,282

FIGURINE OR THE LIKE

Filed April 2, 1949

INVENTOR:
Eulalie Stuart Stauffer

UNITED STATES PATENT OFFICE

160,282

FIGURINE OR THE LIKE

Eulalia Stuart Stauffer, Pacific Grove, Calif.

Application April 2, 1949, Serial No. 1,773

Term of patent 7 years

(Cl. D29—23)

To all whom it may concern:

Be it known that I, Eulalia Stuart Stauffer, a citizen of the United States, resident of Pacific Grove, in the county of Monterey and State of California, have invented a new, original, and ornamental Design for a Figurine or the like, of which the following is a specification, reference being had to the accompanying drawing, forming part thereof.

Fig. 1 is a front view of a figurine or the like, showing my new design. Fig. 2 is a back view thereof and, Fig. 3 is a side view thereof.

I claim:

The ornamental design for a figurine or the like, as shown.

EULALIA STUART STAUFFER.
